UNITED STATES PATENT OFFICE

CLYDE W. STUART, OF NEW YORK, N. Y.

FIBER CONTAINER

Application filed December 24, 1929. Serial No. 416,240.

This invention relates to built-up containers, and particularly to an improved container which may use fiber or paper in forming a large or small basket for the reception of fruit, vegetables or the like, the object being to provide a strong, inexpensive structure which may be shipped knocked-down or built-up.

Another object of the invention is to provide a container which may have the principal parts stamped from a single piece of material and then bent into a desired shape, so that securing bands may be arranged in position to hold the parts in their assembled arrangement.

An additional object, more specifically, is to provide a container which may be made of fiber or paper and which is cut from a single blank with a number of radiating members capable of being bent upwardly to form a substantially solid body when properly secured together. A further object of the invention is to provide a container having a built-up body with rings stapled thereon and metallic handles positioned in suitable apertures in the rings so that when carrying the container by the handles the strain will be distributed more or less evenly throughout the body.

In the accompanying drawings,

Figure 1 is a side view of a basket disclosing an embodiment of the invention;

Figure 2 is a top plan view on an enlarged scale of the body of the basket shown in Figure 1, certain parts being broken away;

Figure 3 is a side view of the body shown in Figure 2;

Figure 4 is a fragmentary sectional view on an enlarged scale of part of the basket shown in Figure 1, the same illustrating how the handle, bottom, rings and associated parts are connected to the body;

Figure 5 is a top plan view of the lid for the basket shown in Figure 1;

Figure 6 is a sectional view through Figure 5 on the line 6-6;

Figure 7 is a plan view of one of the clamping bands shown in Figures 1 and 4;

Figure 8 is a fragmentary perspective

view of the two outside bands shown in Figure 4;

Figure 9 is a sectional view through Figure 8 approximately on line 9-9;

Figure 10 is a fragmentary plan view of a slightly modified form of blank to that seen in Figure 2;

Figure 11 is a fragmentary perspective view showing part of a blank formed as shown in Figure 10 but folded and ready to receive the clamping band and associated members.

Referring to the accompanying drawings by numerals, 1 indicates the body of the basket when completed, as shown in Figure

2, 2 a top band and 3 an intermediate band.

A suitable bottom formation 4 is also provided, the bottom formation and bands 2 and 3 being held in place by staples or other securing means, while the body 1 is made up of two members bent into a desired shape.

In Figure 2 are illustrated blanks 5 and 6, said blanks when properly bent up forming body 1. Each of these blanks is provided with a center section 7 having radiating arms

8 when two blanks are to be formed into a body, the arms 8 of one blank being offset or locked between the arms of the next blank.

As illustrated in Figure 2, an inner bottom plate 4' is provided and an outer bottom plate 4'', said plates being connected together by suitable staples 9 which extend through the center section 7 of the respective blanks

5 and 6. After the parts have been connected together, as shown in Figures 2 and 3, they may be bent up to the shape shown in Figure 1. In order to do this,

a hole 10 is provided in each of the sections 7 and a built-up body is slipped over a spindle or supporting rod in order to hold the structure in place while the different arms 8 are bent up to the desired position.

Before the arms 8 are bent the band 2 is formed into a ring or loop. This band consists of an outer member 11, as shown in Figures 8 and 9 and an inner member 12. These

members are approximately of the same length and are bent into a ring with the ends overlapped slightly (Figure 1) so that when

the staples 13 are applied these members will

be held together and form the ring 2. The outer member 11 is provided with a pair of apertures 14 on diametrically opposite sides of the basket and through these apertures are extended the ends of the respective handles 15, said ends also extending through the slots 16 in member 12. The reason for forming slot 16 is to cause a proper registry in the openings of members 11 and 12, notwithstanding the fact that one moves slightly in a longitudinal direction, while the other remains stationary when the members are bent from the straight position shown in Figure 7 to the looped or ringed position shown in Figure 1. After the ring or loop has been made, as illustrated in Figure 1, the arms 8 are bent up somewhat by the ends and ring 2 slipped thereover from the bottom upwardly. This ring is moved upwardly until it reaches the upper ends of the arms 8 and is then stapled to these arms. Before the stapling operation an inner ring 2' is inserted, as shown in Figure 4, and when the staples are inserted the staples go through ring 2, arms 8 and ring 2'. It will be understood that these staples, as well as all of the other staples, are clinched so as to hold the parts in place. The ends of the handles 15 are also bent over so that they will not readily move out of place. After the bands 2 and 2' have been secured in place the smaller band 3 is slipped over the bottom and secured in place by suitable staples 18. Band 3 is preferably made from two similar strips of fiber or other material which are overlapped at their point of juncture so as to make a strong, independent band before being applied. This band is shown as two ply, though it could be a single band, if desired. When the basket has been completed the arms 8 of the respective blanks practically make a solid body 1, and this body merges into a reinforced bottom 4. In forming the various parts proper proportion is intended, so that when the basket or container is finished it will be of the standard size, as required by the United States Bureau of Standards. This is true regardless of the size of the container. Coating with the container or basket shown in Figures 1 and 4 is a lid 19 which in Figures 5 and 6 is shown on a reduced scale. This lid is formed with a disk 20 of fiber or paper, and to this is secured a corrugated sheet of paper 21. Any desired number of staples 22 may be used to hold the corrugated paper 21 in place. Preferably the disk 20 is provided with a number of slots 23, whereby a desired circulation of air may be had, paper 21 being preferably more or less porous. When the container shown in Figure 4 is filled with fruit lid 19 may be placed thereon and then a second filled container placed on top of lid 19. The corrugated paper 21 helps to distribute the strain over the fruit, so that the stacking of two or

more filled baskets will not injure the fruit.

A number of modified forms may be used in place of section 7 and arms 8 to obtain the same results, in association with the bands 2, 2', 3 and associated parts. One modified form is shown in Figures 10 and 11. From these figures it will be seen that the blank 24 is provided with a solid center 25 having a number of radiating arms 26. Each arm 26 is provided with a short laterally-extending projection 27 and a long laterally-extending projection 28. When the arms are bent upwardly to form the container the extensions 27 and 28 will overlap, as shown particularly in Figure 11. The bands 2 and 3 may then be applied. When the parts are formed in this manner the staples which hold the bands 2 and 3 in place also secure the extensions 27 and 28 in place. From Figure 11 it will be noted that this arrangement of extensions provides a decided reinforcement at the top of the container and also a reinforcement approximately halfway from the top to the bottom. It will be understood that in this form of the invention plates 4' and 4'' are to be used, but preferably only one blank by reason of the special arrangement of the extensions 27 and 28. This structure, therefore, provides a lighter basket than that shown in Figure 1 and yet maintains substantially the same strength by reason of the extensions 27 and 28 and the retaining of the range 2, 2' and 3.

What I claim is:—

1. A built-up container, comprising a body formed from a plurality of blanks, each having a solid integral center with radiating arms integral with the center which when bent up overlap, a pair of rings for holding said arms in their bent formation, one of said rings being arranged at the outer end of the arms, a plurality of staples for each ring for holding the same in place, and reinforcing disks secured to the center interiorly and exteriorly of said blanks. 100
2. A container of sheet material, comprising a body formed from a pair of blanks, each blank having a disk-shaped solid center and a plurality of radiating arms integral with said center, said blanks being offset in regard to each other, so that the arms of one blank will extend into the space between the arms of the other blank, said arms being bent when the blanks are formed into a container structure, a plurality of rings rigidly secured to said arms for holding the same in place, and a reinforcing disk secured interiorly and exteriorly of the body, said disks being secured to the center part of said blanks. 115
3. A basket of sheet material, including a body formed from a blank having a solid center merging into radiating arms, said center being co-extensive with the center of the basket, each arm having a laterally-projecting 120
- 130

extension, whereby when said arms are bent to form a container formation the extensions will overlap, a band fitted over said extensions and staples extending through said band, extensions and arms for rigidly securing the respective members together.

Signed at New York, in the county of New York and State of New York, this 23rd day of December, A. D. 1929.
